(57) CLAIM

The ornamental design for an exercise board, as shown and described.

DESCRIPTION

FIG. 1 is a first perspective view of an exercise board;
FIG. 2 is a second perspective view thereof;
FIG. 3 is a side elevation view thereof;
FIG. 4 is a bottom plan view thereof;
FIG. 5 is a top plan view thereof;
FIG. 6 is a front elevation view thereof; and,
FIG. 7 is a back elevation view thereof.

The broken lines illustrate portions of the exercise board which form no part of the claimed design.

1 Claim, 3 Drawing Sheets

FIG. 3

FIG. 4
